UNITED STATES PATENT OFFICE.

GEORGE W. HOFMANN, OF CHICAGO, ILLINOIS.

LIQUID-FUEL VAPORIZER.

Application filed May 19, 1917. Serial No. 169,622.

To all whom it may concern:

Be it known that I, GEORGE W. HOFMANN, a citizen of the United States, residing at Chicago, in the county of Cook and State 5 of Illinois, have invented certain new and useful Improvements in Liquid-Fuel Vaporizers, of which the following is a specification.

The invention disclosed herein relates to 10 an apparatus and a method for converting into mixed oil gas and vapor any grade of fuel oils, coal tar or by-products thereof, or similar substances, by internally mixing said substances with preheated air in prop- 15 er quantities.

It is well known that for the perfect combustion of any solid or liquid fuels, it is necessary that each particle be surrounded by an atmosphere of oxygen, as in the 20 case of calorimetric determinations. In approaching this condition when using fuel oils, coal tar or their by-products, or similar substances, it is desirable to spray the fluid in order to enable the air supporting 25 combustion to intermingle with the minute particles of the liquid to be burned. The same principle is available in reducing a liquid substance to a gaseous condition.

One of the objects of this invention is to 30 provide an improved method for converting fuel oils, coal tar or their by-products or other similar substances from a liquid to a mixed gas and vapor.

Another object of the invention is to pro- 35 vide such a method in which the nature and composition of the resulting gas and vapor may be readily controlled for the production at will of an oxidizing, neutral or reducing flame, as may be required in various metallurgical and industrial processes.

Another object of the invention is to pro- 40 vide a vaporizer which is adapted to operate upon any grade of liquid fuel without requiring previous special preparation thereof.

Another object of the invention is to cause a rapid and complete breaking up of the liquid fuel, so that the fine particles thereof may be quickly acted upon and effectively converted into gas and vapor, and that no unconverted liquid may be allowed to pass through the gasifier and enter the furnace.

Another object of the invention is to pro- 55 vide an apparatus possessing in a high degree the quality of flexibility for adaptation

to various grades of fuel oil or to other special requirements; for insuring which quality, first, the vaporizer is constructed of separate units, the number of which may 60 readily be increased or decreased; and secondly, these separate units are themselves composed of detachable and interchangeable parts, which parts may be varied in size.

Another object of the invention is to pro- 65 vide a vaporizer which may be readily and quickly inspected for the removal of any solids that may form in its interior.

Another object of the invention is to pro- 70 vide an apparatus in which the danger of damage due to back-firing is eliminated or minimized; and in which such damage as may occur from that cause may be easily and quickly repaired by the substitution of 75 parts.

Another object of the invention is to pro- 80 vide a vaporizer that will insure an even distribution of the mixed gas and vapor about a center line of the vaporizer shown, and therefore an even pressure at the outlet 85 and an equal supply to the various nozzles where a plurality of nozzles are employed.

In the accompanying drawings, Figure 1 is a medial vertical section of a vaporizer 85 embodying the features of my invention. Fig. 2 is a cross-section on the line 2—2 of Fig. 1. Fig. 3 is a cross-section on the line 3—3 of Fig. 1. Fig. 4 is an end view of the oil distributor.

In the embodiment of my invention herein shown I provide a vertical shell, made of cast iron or other suitable material, through which it is intended to pass from top to bottom a volume of preheated air mingled with fuel oils, coal tar or their by-products, or any similar liquid substances. This shell is composed of sectional parts 4, 4^a and 4^b. The number of such parts 4 may be readily increased or decreased to regulate the time limit of travel of the liquid, dependent upon the quantity and quality of the liquid which is to be converted. The parts 4, 4^a and 4^b are held in close contact by three or more bolts 5 passing through lugs 6 formed on the parts 4^a and 4^b, and secured by nuts 7. At the contacting edges the shells 4, 4^a and 4^b are formed with a boss 8 having a half-round groove on its presenting side. When two sections 105 are fitted together, these grooves form an annular tube in which may be compressed 110

a round wick 9 of treated asbestos or other similar material, to prevent leakage of oil gas or air.

Each of the sections 4 and 4^b is offset at 5 its inner upper edge, forming in connection with the next higher section a rectangular groove adapted to receive and hold in position a deflector ring 10 having any suitable diameter of opening in the center. The deflector ring is curved to assist the flow of 10 the air and to catch any particles of fluid not converted, and is formed with a small bead 11 at its inner edge, to aid in the retention and breaking up of the fluids under 15 the influence of the air current.

Midway of each section 4, 4^a and 4^b I provide three or more internal lugs 12, each being cast with a rectangular pocket or depression 12^a. A center plate or baffle 13, of 20 a diameter somewhat less than the diameter of the shell, is formed with round lugs 14 adapted to rest in the depressions 12^a of the lugs 12. To prevent displacement of the center plate by back-fire or other cause, 25 I provide other lugs 15 on the shell immediately above the lugs 12, each of said lugs 15 being cast with a pocket 15^a on its lower face, to register with the similar pocket 12^a on the corresponding lug 12. In case of 30 back-fire, the center plates 13 are adapted to yield, thus tending to prevent breakage, but cannot be displaced from their positions and permitted to fall. The center plate may, however, be easily removed when 35 desired, by lifting the plate and turning it until the lugs 14 are out of register with the lugs 12 and 15; and by reversing this operation another plate may readily be inserted when desired.

40 The center plate 13 is formed with a concavo-convex upper surface, the double curvature serving not only to assist the flow of the air but aiding also in securing, as completely as possible, the mixture of the air and oil or other substance to be converted.

45 The oil, or other substance to be converted into gas and vapor, is admitted to the vaporizer through a pipe 16 inserted in the neck or upper portion of the shell section 4^a. At the end of the pipe 16 is a distributor 50 17 formed of steel or other suitable material and having a deep groove 18 milled on its inner end and adapted to throw a thin horizontal sheet of fluid across the inlet of the shell section 4^a, thus acting as an atomizer and presenting the fluid in finely divided particles for the action of the incoming air. The liquid in the pipe 16 is maintained by 55 any suitable means, at a pressure of from 5 to 15 pounds per square inch or more, dependent on the grade of oil or other substance to be converted. Fuel oil having a paraffin base would not require as high a pressure as heavier oil having an asphaltum base, coal tar, etc. The quantity of liquid 60 65

delivered through the pipe 16 may be regulated by a needle valve (not shown) or other suitable means at the inlet of said pipe.

In operation, preheated air is admitted 70 under a low pressure at the upper or inlet end of shell section 4^a. My experience has shown that the temperature of the air should be between 600 and 850 degrees Fahrenheit, dependent upon the grade of liquid to be 75 converted. The quantity of air may be increased or diminished to vary the oxygen content of the resulting gas, to produce an oxidizing, neutral or reducing flame, as may be desired. The liquid fuel being thrown 80 in finely divided particles across the entering current of air, as hereinbefore described, the more highly volatile part of it is immediately converted into gas and passes quickly around and through the baffles and 85 into the furnace. Such particles of oil as are not immediately converted into gas are carried against the first center plate 13, thence swept by the current of air, aided by the curvature of the center plate, against 90 the wall of the shell, thence upon the first deflector ring 10 where they are checked by the curvature of this deflector ring and by the retaining action of the boss 11, until, by the force of the air current, such particles 95 as still remain in liquid form are further broken up and swept through the central opening of the deflector ring and down upon the next baffle or center plate 13, where the operation is repeated. Upon the surface of 100 each center plate and each deflector ring and upon the side walls of the shell adjacent thereto the liquid is constantly being broken into finer particles until every part of it is converted into a vaporous condition.

105 The action of the heated air in converting the liquid fuel into mixed gas and oil vapor is further aided by the alternate rarefaction and compression of the air and gas during 110 its passage through the shell, due to the fact that it is forced through the openings in the deflector rings and around the center baffle plates and momentarily expands in the relatively large space between them.

115 By reason of the symmetrical arrangement of the openings in the deflector rings and around the center baffle plates, the distribution of gas and oil vapor in passing through the shell is always symmetrical about its center line. This insures an even distribution of the gas and oil vapor at the discharge end of the vaporizer and therefore an equal supply to each of the various nozzles that may be employed to convey the mixed gas and oil vapor to the flames.

120 125 It will be obvious that the principle of my invention is capable of application in various ways, and I do not limit myself to the particular form of apparatus herein shown and described.

I claim as my invention:

1. A vaporizer containing center plate baffles, means for securing such baffles against rotation and displacement in one direction and means to limit their displacement in the opposite direction, thereby providing against danger of breakage from backfire.
2. A fuel vaporizer comprising a shell made in detachable units and containing center plate baffles, means on the interior of the shell for securing such baffles against displacement in the direction of the flow of the fuel in the process of vaporization, and means to limit displacement in the reverse direction thereby providing against danger of breakage from backfire.
3. A fuel vaporizer comprising, in combination, a shell made in detachable units; and means for the introduction of a current of air; an oil distributor having a narrow transverse aperture opening into the shell and adapted to throw the liquid fuel across the current of air in a thin sheet or spray, and a series of baffles removably mounted within said shell.
4. In a liquid fuel vaporizer, in combination, a shell; means for the introduction of a

current of air; means for spraying fuel oil across said current; a series of alternating center plate baffles and deflector rings, both baffles and rings having that surface which is presented to the current of air and oil vapor curved in such manner as to reflect such current at the edge of their respective passageways whereby the agitation of the mixture is increased at the place of passage.

5. In a liquid fuel vaporizer, a shell adapted to convey a current of air and oil vapor; and a series of center plate baffles, each of which presents to such current a double curved surface adapted to throw the current back upon itself at the edge of the baffle plate, whereby the agitation of the mixture is increased.

6. In a liquid fuel vaporizer, a shell adapted to convey a current of air and oil vapor, and a series of deflector rings having each a central opening, said deflector rings having a recurved surface adapted to throw said current back upon itself at all points around the edge of such opening whereby the agitation of the mixture is increased.

In testimony whereof, I have hereunto set my hand.

GEORGE W. HOFMANN.
